AKTIEBOLAG, OF JYVÄSKYLÄ, FINLAND, A COMPANY INCORPORATED IN FINLAND.

PROCESS FOR MAKING LINES AND WATER-MARKS ON PAPER AND APPARATUS THEREFOR.

1,329,100.

Specification of Letters Patent.

Patented Jan. 27, 1920.

Application filed August 13, 1919. Serial No. 317,278.

To all whom it may concern:

Be it known that I, ONNI SUURSALMI, of Jyväskylä, Finland, manager of paper works, a citizen of Finland, have invented a 5 certain new and useful Improved Process for Making Lines and Water-Marks on Paper and Apparatus Therefor, of which the following is a specification.

This invention relates to processes for 10 making lines and water marks on paper during its manufacture and to apparatus for carrying out such processes.

The object of the invention is to provide 15 an improved process of the above indicated kind which can easily be carried out and be regulated with accuracy during the manufacture of the paper.

In the operation of papermaking machines 20 as heretofore employed, the pulp from which the paper is made is passed along on an endless moving belt or strip of cloth through which the water filters away leaving a fibrous material on the cloth from which the finished paper is produced. For the purpose of 25 further drying the paper the endless cloth is led over vacuum boxes which do not effect any marking of the paper and in some cases is led between rolling presses, calendering rolls or the like.

30 In the improved process according to this invention a regulated flow of water is supplied at a series of predetermined points to the under side of the endless cloth and thence to the pulp thereon which is thus loosened in 35 passing over those points, while simultaneously a regulated suction effect is applied at a series of other predetermined points to the under side of the endless cloth, so that as the cloth passes over these points part of the 40 pulp is moved away from the first mentioned series of points and is drawn toward the second mentioned series of points, thus making the pulp thinner at the former and thicker at the latter points and causing the paper to be 45 marked in a corresponding manner.

For the purpose of carrying out the invention I make use of a special apparatus which I call a marking box, an end view and a plan of which are illustrated in the accompanying 50 drawings.

Figure 1 is an end view of the marking box and Fig. 2 is a plan view.

Referring to the drawings, the marking box consists of two chambers A and B and is

shown arranged with its length transversely 55 across the path of the endless circulating cloth D moving in the direction of the arrow and carrying a sheet of pulp P the cover of the marking box being shown at L.

The chamber A of the marking box is supplied with water from any suitable source by means of a pipe (not shown) containing means for very accurately regulating the pressure of the flow therethrough and for totally shutting off the supply when desired; 60 for this purpose any suitable or known regulating device may be used. The chamber B is connected to the vacuum pump or other exhausting device attached to the paper machine, or may be connected to a separate 65 exhausting device of any suitable kind (not shown), and this connection also is provided with any suitable or known vacuum-regulating means.

In the cover L of the marking box two 75 series of passages or openings H' and H₂ are formed, one series H' connected to the water chamber A and the other series of passages H₂ connected to the vacuum chamber B. The upper ends of these passages terminate 80 in openings in the cover L of the marking box which openings may be arranged in any desired manner according to the nature of the marks which it is desired to impart to the paper under treatment. In the arrangement shown all the openings in the cover of the marking box are arranged in one straight line and consequently are adapted to form straight line marks upon or within the substance of the paper as it is carried over the 85 90 openings by the endless cloth D.

In operation the pressure water from chamber A of the marking box being admitted to the passages H' and the suction action from chamber B being admitted 95 to the passages H₂ it will be seen that a series of pressure points and a series of suction points are encountered by the under side of the endless cloth D and thence by the sheet of pulp P as these move over the 100 marking box. The effect of this simultaneous operation of pressure at some points and suction at other points is that the pulp is loosened and forced away from the former and is drawn to the latter points thus making the pulp sheet thinner at the pressure points and thicker at the suction points and causing lines called water-marks to appear 105

in the substance of the paper. The particular effect produced upon the paper depends upon the arrangement of the upper openings of the passages H' and H_2 in the cover 5 of the marking box, and the nature of the pressure and suction actions, that is, whether these are continuous or intermittent. It is not necessary to arrange the said openings in a straight line but they may be arranged 10 in any desired order and the two series may be displaced relatively to each other so that the sheet D will first pass pressure openings and then suction openings. Also the openings of the connecting passages H' and H_2 15 may be given any desired shape, for instance, either round or oval. The marking box may be connected, if desired, with the usual vacuum box of a paper machine and may be fitted with the usual regulator employed therewith.

It will be evident that the details both of the improved process and also of the construction of the marking box employed may be conveniently varied without exceeding the scope of the invention.

What I claim and desire to secure by Letters Patent is:—

1. The process of making lines and water marks on paper during manufacture of the latter which consists in providing a series 30 of apertures arranged in a manner corresponding to the desired lines or marks at predetermined points in the path to be traversed by the paper pulp during manufac-

ture, and supplying a regulated flow of 35 water to some and a regulated suction effect to others of the said apertures as the said paper pulp passes over them.

2. Apparatus for making lines and water marks on paper during manufacture, comprising a marking box, a partition therein 40 dividing the interior of the box into two chambers, means for supplying water to one chamber, means for creating a vacuum in the other chamber, a series of apertures 45 arranged in the path of the paper pulp so as to correspond to the desired lines or marks, and means for connecting the water chamber of the marking box to some of the said apertures and the vacuum chamber to others 50 of the said apertures.

3. Apparatus for making lines and water marks on paper during manufacture, comprising a marking box, a partition therein dividing the interior of the box into two 55 chambers, means for supplying water to one chamber, means for creating a vacuum in the other chamber, a series of apertures arranged in the path of the paper pulp to correspond to the desired lines or marks 60 and means for connecting every alternate aperture to the water chamber and the intermediate apertures to the vacuum chamber of the marking box.

ONNI SUURSALMI.
